ORLANDO V. FLORA, OF MADISON, INDIANA, ASSIGNOR TO HIMSELF
AND WILLIAM A. COLLINS, OF THE SAME PLACE.

Letters Patent No. 65,898, dated June 18, 1867.

IMPROVED VISE.

The Schedule referred to in these Letters Patent and making part of the same.

TO ALL WHOM IT MAY CONCERN:

Be it known that I, ORLANDO V. FLORA, of Madison, in the county of Jefferson, and State of Indiana, have invented a new and improved Adjustable Parallel Vise; and I do hereby declare that the following is a full, clear, and exact description thereof, which will enable others skilled in the art to make and use the same, reference being had to the accompanying drawings, forming part of this specification, in which—

Figure 1 is a perspective view of my improved vise.

Figure 2 is a detail sectional view taken through the line *xx*, fig. 1.

Figure 3 is a detail view showing the manner in which the front jaw is pivoted to the sliding-bar.

Figure 4 is a detail sectional view taken through the line *yy*, fig. 3.

Similar letters of reference indicate like parts.

My invention has for its object to furnish an improved vise which can be readily and quickly adjusted to the size of the object to be held, and which will adjust itself to the shape of the object to be held, whether its sides be parallel or inclined; and it consists in the construction of the rear jaw, in the combination and arrangement of the parts by which the front jaw is pivoted to the sliding-bar, and in the combination of the sliding-bar, support, and jaws of the vise, the whole being constructed and arranged, as hereinafter more fully described.

A is the bench, to which the vise is attached. B is the support, which is screwed fast to the bench A, and which is slotted vertically for the reception of the sliding-bar C and of the tenon or tongue formed upon the lower part of the rear jaw D. The sliding-bar C is formed with flanges upon its upper and lower edges, fitting into grooves formed in the support B, so as to compel the said bar to move back and forth in a straight line; and it has ratchet-teeth formed upon its upper edge for the lower end of the rear jaw D to take hold of to hold the parts of the vise in place while clamping the object to be held. E is a spring, one end of which is attached to the lower end of the rear jaw D, and the free end of which rests upon the upper edge of the sliding-bar C. The spring E, as soon as the pressure upon the jaws is removed, lifts the lower end of the rear jaw D away from the teeth of the sliding-bar C, and allows the said bar to be moved freely out and in. The forward end of the sliding-bar C is enlarged, as shown in fig. 3, and has a vertical hole formed through it for the reception of the pivoting pin of the nut F, to the lower end of which is pivoted the lower end of the front jaw G, as shown in figs. 1 and 3. H is the screw, by means of which the object to be held is clamped between the jaws D and G. The screw H passes through a hole in the body of the front jaw G, and screws into the nut F, the head of the screw pressing against the side of the jaw G. I is a spring, one end of which is attached to the inner side of the jaw G, and the other end presses against the forward end of the sliding-bar C to throw the said jaw G back whenever released from the action of the screw H. J is a key, placed between the pivoting pin of the nut F and the bottom of a notch formed in the end of the sliding-bar C, as shown in fig. 3. In the side of the said pivoting pin, which is directly opposite the end of the said sliding-bar when the jaws of the vise are parallel with each other, is formed a notch into which the key J may be forced to secure the jaw G in that position, and by driving the key back the jaw will be again free to adjust itself to the form of the object to be held. By this construction and arrangement of the parts the screw H may be made short, as but one or two turns of said screw will ever be required to clamp the object to be held.

In using the machine the jaw G and sliding-bar C are drawn out, the object to be held is placed between the jaws, and the sliding-bar C and jaw G pushed back until the jaw G comes in contact with and adjusts itself to the object to be held. One or two turns of the screw H will then clamp it securely in place.

What I claim as new, and desire to secure by Letters Patent, is—

1. The rear jaw D, constructed substantially as herein shown and described, in combination with the support B and sliding-bar C, as and for the purpose set forth.
2. The front jaw G, pivoted at its lower end to the lower end of the vertical pin bearing the nut F, and fitting in the vertical hole of the sliding-bar C, as herein set forth for the purpose specified.
3. The combination and arrangement of the front jaw G, short screw H, nut F, and sliding-bar C, with each other, substantially as herein shown and described and for the purpose set forth.
4. The combination of the key J with the end of the sliding-bar C, and with the pivoting pin of the nut F, substantially as herein shown and described, and for the purpose set forth.
5. The combination of the support B, sliding-bar C, and jaws D and G, with each other, substantially as herein shown and described and for the purpose set forth.

ORLANDO V. FLORA.
